UNITED STATES PATENT OFFICE.

GEORGE W. PIERCE, OF DAVIS, CALIFORNIA, ASSIGNEE TO CALIFORNIA ALMOND GROWERS EXCHANGE, OF SAN FRANCISCO, CALIFORNIA, A CORPORATION OF CALIFORNIA.

METHOD OF TREATING ALMONDS.

Application filed February 16, 1922. Serial No. 536,811.

To all whom it may concern:

Be it known that I, GEORGE W. PIERCE, a citizen of the United States, residing at Davis, in the county of Yolo and State of California, have invented certain new and useful Improvements in Methods of Treating Almonds, of which the following is a specification.

The present invention relates to the treatment of almonds preliminarily to the bleaching thereof, the object thereof being to dampen and moisten the almonds so as to render the shell more susceptible to the action of the sulphur fumes during the bleaching of the almonds and further for a sterilization of the almonds to be bleached in order to destroy all germ life.

The method invention resides in advancing of almonds as a continuous flow stream through a cylinder or drum maintained in rotation, retarding the flow of the stream of almonds while maintaining the same under agitation, subjecting the moving body of almonds to the direct action of jets of live steam for the sterilization thereof and a moistening of the shells to render the almonds more susceptible to the effects of the sulphur fumes when subjected to bleaching.

Under this method of treating the almonds preliminarily to the bleaching thereof, the same are placed in better condition for bleaching than heretofore and leave the bleaching apparatus in better condition for marketing, while at the same time all germ life is destroyed which insures the keeping of the almonds without danger of becoming worm eaten.

The apparatus for a carrying out of the method invention is disclosed in the accompanying sheets of drawings, wherein:—

Figure 1 is a side view of the apparatus partly broken away.

Figure 2 is a top plan view of the apparatus.

Figure 3 is a sectional end elevation taken from the feed end of the apparatus and viewed in the direction of the arrow, Figure 1 of the drawings.

Figure 4 is a similar view taken from the discharge end of the apparatus, viewed in the direction of the arrow.

In the drawings, the numeral 1 is used to designate any suitable form of a supporting or frame structure, within which is mounted for rotation a longitudinally disposed

cylinder or drum 2, which stands at a slight downward inclination toward its discharge end. This cylinder or drum in the present case is formed of corrugated galvanized iron and the same is supported exteriorly by tread rollers 3—4 mounted in bearings of the semi-cylindrical or cradle supporting brackets 5—6 secured to the frame structure adjacent the feed and discharge end portions respectively of the cylinder or drum 2. The tread rollers 3—4 bear onto the flanged tread rings 7—8 secured to and encircling the cylinder or drum 2 adjacent its end portions and the thrust of the said cylinder during its rotary movement is taken care of by the thrust rollers 9, which act against the outstanding flange 10 of the tread ring 8. The outer face of the flange 10 of the tread ring 8 is formed into a gear ring 11, which meshes with a pinion 12 secured to the inner end of a short shaft 13 adapted to be coupled to a power driven belt pulley 14 through the medium of a hand actuated clutch 15, the pulley 14 being driven from any suitable source of power means.

The cylinder or drum 2 is provided interiorly with a continuous helical conveyer flight 15', which serves during the rotary movement of the said cylinder or drum to gradually move or advance the almonds therethrough from its feed toward the discharge end thereof, the said helical conveyer flight retarding or checking the free flow action of the almonds. During their course of travel through the cylinder or drum, the almonds are thoroughly agitated and turned over and over.

Within the cylinder or drum 2 is extended a perforated spray pipe 16 through which live steam is forced under pressure, which escapes therefrom within the drum as jet streams. The steam thus ejected from the perforated spray pipe 16 is directed onto the almonds as advanced through the cylinder or drum, dampening and moistening their shells to render the same more susceptible to effect of the sulphur fumes when the almonds are subjected to the bleaching process, while at the same time the high temperature of the live steam ejected or sprayed onto the almonds sterilizes the same and destroys all germ life.

The feed end of the cylinder or drum 2 is closed by a drum head 17 provided with a central opening 18 through which is ex-

tended the steam spray pipe 16, as well as the lower end of the almond feed chute 19.

Preferably the cylinder or drum 2 is in length approximately twelve (12) feet and 5 of a diameter approximately three (3) feet.

By the interposition of the helical conveyer flight within the cylinder or drum, the almonds are conveyed therethrough as a continuous stream of retarded movement, 10 the time required for the almonds in passing through the cylinder or drum being regulated by the speed at which the same is rotated per minute or by the spacing of the spiral divisions of the conveyer arranged 15 therein, or by extending or shortening the length of the cylinder or drum.

Having thus described my invention, what I claim as new and desire to secure by Letters Patent of the United States is:—

A continuous method of treating almonds 20 which consists in advancing the same in a continuous flow stream through a cylinder or drum maintained in rotation, retarding the flow of the stream of almonds while the same are under agitation, and continuously 25 subjecting the moving body of almonds under agitation to the direct action of jets of live steam to penetrate the shell, sterilize the same and sterilize the meats.

In testimony whereof I have signed my 30 name to this specification.

GEORGE W. PIERCE.
